LABEL PRINTING DEVICE

Donald R. Draper, Detroit, Mich.

Application July 21, 1952, Serial No. 300,037

1 Claim. (Cl. 101—92)

This invention relates to label printing and cut-off devices for producing individual labels from a continuous strip of tape.

One object of this invention is to provide a machine which may be manually or power operated for turning out labels from a continuous strip of tape, without any special attention being required on the part of the operator. Thus, unskilled operators may be employed while at the same time maintaining a high quality and uniformity of label production.

A further object of this invention is to provide a machine of the above type wherein such labels may be separated or cut from a strip of tape automatically and in synchronism with the stamping of the same.

Still another object of this invention is to provide means for maintaining a large number and variety of different stamping blocks in standby condition whereby the latter may be quickly and easily transferred to operative position in the machine or exchanged for others, in order that the machine may be set up without delay for the production of a different type label.

A further object of this invention is to provide means for retaining the stamping blocks in stand-by position without obstructing observation of the indicia thereon so that the desired block may be selected without delay.

Another object of this invention is to provide a label stamping and cut-off machine which is inexpensive and substantially fool-proof in operation.

The foregoing, as well as other objects, will be made more apparent as this description proceeds, especially when considered in connection with the accompanying drawings, wherein:

Figure 1 is a front elevation of a machine embodying the features of the present invention;

Figure 2 is a top plan view of the machine shown in Figure 1;

Figure 3 is a vertical sectional view of the machine taken along the line 3—3 on Figure 1;

Figure 4 is a view similar to that of Figure 3, but taken along the line 4—4 on Figure 1;

Figure 5 is a fragmentary side elevational view of the machine as seen from the right-hand side of Figure 1;

Figure 6 is a fragmentary perspective view of the machine;

Figure 7 is a fragmentary detail illustrating the feeding mechanism employed in the machine; and,

Figure 8 is a perspective view of a stamping block which may be employed in the operation of the machine.

Referring now to the drawings, the machine there illustrated embodies a preferred form of my invention and includes side frames 1 and 2, and an intermediate frame or panel member 3, which are secured together by suitable bolts 4, to form a rigid upright structure. An angle iron 4' interconnects frame member 3 and the base of the structure by means of the bolts or rivets shown. Member 5, across the front of the machine, further rigidifies the structure and will be described in more detail below.

The tape feeding mechanism will be seen to comprise a shaft 6 rotatably mounted between frame members 1 and 3, having a wheel sector 7 non-rotatably mounted thereon. Screw 8 affords an adjustable non-rotatable connection between wheel sector 7 and shaft 6 when advanced tightly into engagement with the latter. (See Figure 4.)

A strip of resilient material 9, secured to wheel sector 7 and projecting beyond the periphery thereof, is provided to engage and advance a strip of tape 10 as the

2

wheel sector is rotated by means of crank arm 11 projecting from shaft 6. The feeding strip 9 may have printing matter on the outer surface thereof to mark tape 10 as it is thus advanced. Such tape may be drawn from a roll of the same supported on shaft 12, for example, journaled between frame members 1 and 3, at the rear of the machine. A roller 13, mounted between frame members 1 and 3 on a shaft parallel to that of wheel sector 7 and with its outer surface spaced slightly from that of feeding strip 9, cooperates with the latter in advancing the tape 10 by underlying the latter at the point of contact thereof with such feeding strip. Roller 13 may be of a resilient material or provided with a resilient covering projecting into actual engagement with feeding strip 9, thereby to afford more positive advancement of the tape.

Member 5, across the front of the machine, is held in place by means of studs 14 on one end thereof projecting through complementary holes in frame member 2, and studs 15, on the opposite end thereof having reduced portions fitting into notches of frame member 1. Member 5 is formed with an elongated horizontal U-shaped notch 16 for travel therethrough of the tape 10 during advancement thereof by the feeding mechanism above described.

Rotatably mounted on the front face of member 5 by means of stub shaft 17 is a cut-off member 18 having a knife 19 integral therewith and swingable across the opening provided by notch 16. Member 20, secured to the upper face of notch 16, provides a knife edge which cooperates with knife 19 to sever sections of tape extending through the notch. Tension spring 21, extending between frame member 1 and pin 22 of the cut-off member, serves normally to hold the latter retracted with knife 19 below notch 16. As will be seen in Figures 1, 5 and 6, crank arm 11 is formed with an intermediate portion extending along the side of the machine adapted to engage the end portion 19' of knife 19 to turn the latter in an upward direction about the shaft or pivot 17 across notch 16 and, in cooperation with member 20, to shear sections from the end of tape 10 when such crank arm is turned in a clockwise direction as viewed in Figure 5. Upon further clockwise rotation of the crank arm, the same will cam past end portion 19' of the knife permitting the latter to return to its normal position below notch 16 under the influence of tension spring 21. Actuation of knife 19 will thus be seen to occur once in each revolution of the crank arm.

Wheel sector 7 will be seen to have a plurality of axially extending ribs 23 thereon, equally spaced apart to form grooves 24 therebetween. While, as will be seen in Figure 4, such ribs do not project sufficiently to engage tape 10 as it is advanced by feeding strip 9, the stamping blocks, generally indicated at 25 and adapted to fit snugly in grooves 24, are so dimensioned as to project when thus inserted in their respective grooves to a point substantially flush with the outer periphery of feeding strip 9, and thus to make contact with tape 10 and mark the latter with printing matter. Roller 13 will desirably also underlie the tape 10 at the point of engagement of the stamping blocks therewith in order to provide a firm backing for the strip during the stamping operation. As seen in Figure 8 stamping blocks 25 may comprise a stamping block proper 26 inserted in a channel-shaped member 27 of ferrous material having spring clips 28 for retaining the blocks therein. Magnets 29 disposed in grooves 24 on the periphery of the wheel sector serve to retain the stamping blocks securely therein.

An inking roll 30, rotatably mounted between frame members 1 and 3, is positioned in a manner such that the outer inked surface thereof is contacted by the stamping blocks and feeding strip 9 upon each revolution of wheel sector 7. Such inking roll is journaled in inclined slots 31 in frame members 1 and 3 to permit a degree of movement of the roll when thus contacted during operation of the machine. Slots 31 are open at their upper ends to permit insertion of inking roll 30.

Rotatably mounted between frame members 2 and 3 is a shaft 32 having a wheel 33 non-rotatably mounted thereon. Wheel 33 is of a large diameter as compared with wheel sector 7 and like the latter has formed on its outer periphery a plurality of axially extending ribs 34 equally spaced apart to form grooves 35, the latter

having substantially the same dimensions as grooves 24 of the wheel sector. As seen in Figures 4 and 6, the shaft of wheel 33 is parallel to that of wheel sector 7 and disposed so that the peripheries of the wheel and wheel sector lie substantially flush at one point. Thus, wheel 33 may be employed to store a large number and variety of different stamping blocks in standby condition which may be readily transferred to wheel sector 7 to perform a printing operation. Stamping blocks 25 are retained in the grooves of wheel 33 by means of a flexible plastic band 36 encircling wheel 33, such band preferably being of transparent material so as not to obstruct the indicia on the blocks to facilitate selection of the desired one without delay.

In the operation of the machine described above, the same will first be set up by drawing the strip of tape 10 through notch 16 and placing selected stamping blocks in the grooves of the wheel sector. Such blocks may be easily transferred from standby position on wheel 33 by merely aligning the groove 35 containing the selected stamping block with a groove of wheel sector 7 and then sliding such stamping block from one groove to the other, magnets 29 of wheel sector 7 serving to grip the blocks even before they are fully withdrawn from the grooves of wheel 33. The transparency of band 36 permits quick selection of the desired stamping block while it is held on wheel 33. Feeding strip 9 will be seen to be secured in notches formed in ribs 23 so that the inner surface of the feeding strip lies flush with grooves 24, thereby forming an abutment at the end of grooves 24 remote from wheel 33 whereby to properly position the stamping blocks thereon. Thereafter, continuous operation of the machine is obtained merely by turning crank arm 11 which serves intermittently to advance the strip of tape as feeding strip 9 engages such tape and simultaneously to stamp advancing sections of the tape with the desired markings. Crank arm 11 and wheel sector 7 are secured on shaft 6 in angular relationship such that towards the end of each intermittent advance of the tape the forwardmost section thereof is cut off by actuation of knife 19. (See Figure 5.) In this adjusted angular relationship it will be understood that following cut off of the printed label at the end of the tape the latter is slightly further advanced so that the end thereof projects beyond the notch opening 16 whereby it may be adjusted by hand between intermittent advances of the tape if desired. Since wheel sector 7 is adjustably mounted on shaft 6 it is apparent that the cut-off operation may be made to occur between advances of the tape, rather than just prior to the end of each advance as in the embodiment shown.

The drawings and foregoing specification constitute a description of the improved label printing and cut-off

device in such full, clear, concise and exact terms as to enable any person skilled in the art to practice the invention, the scope of which is indicated by the appended claim.

What I claim as my invention is:

In a label printing machine, two wheels journaled side by side on parallel axes, said wheels each having a plurality of axially extending ribs on their peripheries defining grooves for receiving and holding label printing means, said wheels being mounted in a manner such that their grooved peripheries are substantially flush at least at one point, whereby such label printing means may be transferred from one said wheel to the other, and means for advancing a length of tape past one of said wheels, said tape advancing means comprising a circumferentially extending feeding strip on said last-named wheel projecting radially beyond the ribs thereon, said feeding strip being adjacent the side of said last-named wheel remote from the other said wheel, thereby serving also as an abutment to properly locate such label printing means in the respective grooves of said last-named wheel, magnetic means on said last-named wheel adapted to hold such label printing means in the respective grooves thereof, and a transparent plastic band encircling the other of said wheels adapted to hold such label printing means in the respective grooves.
